UNITED STATES PATENT OFFICE

JOHN J. WOMPEY, OF DENVER, COLORADO

ILLUMINATING DEVICE

Application filed March 5, 1929. Serial No. 344,367.

This invention relates to illuminating devices and its main object is to provide an illuminating unit in which a light of very high intensity is economically produced with a minimum expenditure of electric current, or other light-producing medium.

A further object resides in the provision of an arrangement of parts by which a surface of considerable length may be evenly illuminated and with great brilliancy, by the use of a single lamp of low candle power placed at an end thereof, and still other objects are to be found in details of construction and will be fully brought out in the course of the following description.

My invention is particularly adapted for the illumination of signs although it may be used with good effect for general lighting purposes, and it is in the form of a sign that the invention has been illustrated in the accompanying drawings.

Figure 1 of the drawings represents a longitudinal section in a horizontal plane, of a sign in which the distinctive features of the invention are embodied,

Figure 2, a face view of the sign shown in Figure 1,

Figure 3, a transverse section along the line 3—3, Figure 2,

Figure 4, a transverse section taken on the line 4—4, Figure 2,

Figure 5, a perspective view of a portion of a prismatic plate used as an element of the invention,

Figure 6, a sectional view similar to Figure 1, but drawn to a smaller scale, showing a modified form of the invention, and

Figure 7, a section similar to Figure 6 illustrating another modification of the invention.

Like reference numerals designate corresponding parts throughout the views.

The illuminating unit as shown, comprises an elongated box 5 of preferably rectangular section, the open front of which is closed by means of a plate 6 of prismatic glass.

This glass as shown in Figure 5, has a ribbed surface and for the purpose of the present invention it is preferred to have the ribs 7 extend transversely of the plate with respect to the longitudinal extent of the box

and to place the plate in the opening of the box with its ribbed surface innermost. Each rib of the glass plate represents a prism adapted to bend rays of light directed at an acute angle to the plate, at an angle to the surface of the same. Certain rays will pass directly through the plate but others are reflected at an angle and directed against the reflector 14. Those rays which are deflected from the reflector 14 are refracted by the glass plate and leave the latter on lines at a right angle thereto.

The source of light consists of a single incandescent lamp 8 placed at an end of the box in the axis of a concentrating reflector 9. The reflector is preferably of parabolic form but the shape of its reflective surface may be varied from a true parabolic curve according to varying requirements. It is to be understood, however, that a reflector of high concentrating efficiency is an important part of the invention.

The lamp and the reflector are conjointly adjustable to vary the direction of the axis of the beam of light produced in the source, with relation to the illuminating surface provided by the transparent plate covering the opening of the box. The lamp and the reflector are for this purpose mounted on a support 10 that is pivotally mounted as at 12 on a bracket 13 fastened to the rear wall of the box.

An opening 21 normally closed by a cover 22, affords access to the source of light for its adjustment or renewal.

Rearward of the transparent illuminating surface, within the box, is a preferably reflective back 14 that slants from a point adjacent the reflector in the rear wall of the box to a point closely adjacent the illuminating surface at the end of the box opposite to that at which the source of light is located.

The back has for its object to confine the light rays to the beam thrown out by the source of light and to thereby conserve the illuminative intensity of the beam throughout its length.

The back is curved at its end adjacent the source of light, as shown in Figure 3, and its curve diminishes gradually until at its end

at which it approaches the illuminating surface it is substantially straight, as indicated in Figure 4.

5 In Figure 1 the broken lines 15 indicate the beam of light produced in the source and directed toward the prismatic plate that closes the opening of the box.

10 The lamp is in the focus of the reflector and the light source is adjusted to a position in which the axis 16 of the light beam coincident with that of the reflector, strikes the illuminating surface at a point at substantially equal distances from its ends, while the rays 15 at the periphery of the beam strike the reflective surface at its ends.

15 The reflective back 14 aids in diffusing the light beams with uniform intensity throughout the length of the box and each light ray of the beam is bent as it strikes the prismatic 20 surface of the plate 6 to be propagated at right angles through the plate, as indicated at 17.

25 Moreover, the rays from the lamp and the parabolic reflector strike the prisms at such an angle that the bent surfaces of the prisms reflect the light rays against the reflector 14. The latter reflects the rays and directs them towards the prisms on lines which are sufficiently near the normal that they pass through the plate 6 and illuminate the sign.

30 The device thus constructed has extremely high illuminative power in proportion to the amount of current consumed in the source of light and it is a distinctive feature of the device that the propagated light is of substantially uniform intensity throughout the length of the illuminating surface despite the fact that the source of light is located at one end thereof.

35 To use the illuminating unit as a sign, a sheet of glass 18 bearing the letters or other characters of the sign, may be placed in front of the prismatic plate, or the letters or other designs may be painted directly upon the smooth outer surface of the plate.

40 45 Either or both the glass plate 6 and the sheet of glass 18 may be colored and the letters of the sign may be transparent or translucent upon an opaque background, as indicated in Figure 1.

50 55 It will be understood that various effects too numerous to mention, may be produced by varying the colors or designs on the prismatic plate or the sheet of glass covering the same.

The invention is subject to several modifications within its scope and spirit as defined in the hereunto appended claims.

55 60 For example, two or more illuminating elements, each having a prismatic surface may be simultaneously lighted from one and the same source of light at an end of the box, as illustrated in Figure 6.

65 The lamp is in this form of the invention, placed out of the focus of the reflector so that two intersecting beams are directed toward the two prismatic panes of glass.

70 The longitudinal reflector has two parts 19 slanting from points adjacent the prismatic plates at the end of the box opposite to that at which the source of light is located, to a point of intersection in the axis of the source which in this instance is substantially parallel to the illuminating surfaces.

75 It will be apparent that in this manner a sign or illuminating unit having three, four or more illuminating sides, may be produced and that even a unit having a cylindrical illuminating surface may be effectively operated.

80 It is also to be understood that in signs bearing a number of lines of advertising matter or being generally of greater width, two or more sources of light may be placed one above another at the end of the box.

85 Inasmuch as all of the above mentioned modifications are mere duplications of the forms shown in the drawings, it has been thought unnecessary to further illustrate the same.

90 In Figure 7, has been shown an illuminating unit of greater length. Two sources of light are disposed at opposite ends of the box, and the longitudinal reflectors 20 back of the prismatic plate slant toward a meeting point in the center of the unit.

95 What I claim and desire to secure by Letters Patent is:

100 1. An illuminating device comprising a box having an open front, a plate covering the opening of the front, and having a ribbed surface providing a series of prisms adapted for the reflection of light at substantially right angles to the front, a lamp in the box, at an end of the opening, a reflector slantingly disposed to direct the light from the lamp toward the opening, and a reflective back slanting from adjacent the lamp toward the opening, to form with the plate a gradually tapering enclosure, adapted to equalize the intensity of the light rays longitudinally of the opening.

105 110 2. An illuminating device comprising a box having an open front, a plate covering the opening of the front, and having a ribbed surface providing a series of prisms adapted for the reflection of light at substantially right angles to the front, a lamp in the box, at an end of the opening, a parabolic reflector slantingly disposed to direct the light from the lamp toward the opening, and a reflective back slanting from adjacent the lamp toward the opening, to form with the plate a gradually tapering enclosure, adapted to equalize the intensity of the light rays longitudinally of the opening.

115 120 125 3. An illuminating device comprising a box having an open front, a plate covering the opening of the front, and having a ribbed surface providing a series of prisms adapted for the reflection of light at substantially right angles to the front, a lamp in the box,

at an end of the opening, a reflector slantingly disposed to direct the light from the lamp toward the opening, and a transversely curved reflective back slanting from adjacent the lamp toward the opening, to form with the plate a gradually tapering enclosure, adapted to equalize the intensity of the light rays longitudinally of the opening.

4. An illuminating device comprising a box having an open front, a plate covering the opening of the front, and having a ribbed surface providing a series of prisms adapted for the reflection of light at substantially right angles to the front, a lamp in the box, at an end of the opening, a reflector slantingly disposed to direct the light beam from the lamp toward the opening so that the axis of the beam strikes the plate centrally of the opening, and a reflective back slanting from adjacent the lamp toward the opening, to form with the plate a gradually tapering enclosure adapted to equalize the intensity of the light-rays longitudinally of the opening.

5. An illuminating device comprising a box having an open front, a plate covering the opening of the front, and having a ribbed surface providing a series of prisms adapted for the reflection of light at substantially right angles to the front, a lamp in the box, at an end of the opening, a reflector slantingly disposed to direct the light beam from the lamp toward the opening so that the axis of the beam strikes the plate centrally of the opening, and a reflective back slanting from adjacent the lamp toward the opening in a direction substantially parallel to that of the axis of the light-beam, to form with the plate a gradually tapering enclosure adapted to equalize the intensity of the light rays longitudinally of the opening.

6. An illuminating device comprising a box having an open front, a plate covering the opening of the front, and having a ribbed surface providing a series of prisms adapted for the reflection of light at substantially right angles to the front, a lamp in the box, at an end of the opening, a reflector slantingly disposed to direct the light from the lamp toward the opening, and a reflective back slanting from adjacent the lamp toward the opening, to form with the plate a gradually tapering enclosure adapted to equalize the intensity of the light rays longitudinally of the opening, the lamp and the reflector being entirely concealed by the part of the front forward of the adjacent end of the opening.

7. An illuminating device comprising a box having an open front, a plate covering the opening of the front, and having a ribbed surface providing a series of prisms adapted for the reflection of light at substantially right angles to the front, a lamp in the box, at an end of the opening, a reflector slantingly disposed to direct the light from the

lamp toward the opening, and a reflective back slanting from adjacent the lamp toward the opening, to form with the plate, a gradually tapering enclosure adapted to equalize the intensity of the light rays longitudinally of the opening, the reflective back being transversely curved and the curvature of the back diminishing gradually from its end adjacent the lamp to its opposite end.

In testimony whereof I have affixed my signature.

JOHN J. WOMPEY.
